UNITED STATES PATENT OFFICE

164,701

FONT OF NUMERALS

Francis E. Meyer, Lancaster, Pa.

Application November 4, 1950, Serial No. 12,849

Term of patent 14 years

(Cl. D64—12)

To all whom it may concern:

Be it known that I, Francis E. Meyer, a citizen of the United States, residing in the city of Lancaster, county of Lancaster, State of Pennsylvania, have invented a new, original, and ornamental Design for a Font of Numerals, of which the following is a specification, reference being had to the accompanying drawing, forming a part hereof.

The drawing illustrates face views, slightly in perspective, of a font of numerals, showing my new design, said new numerals representing individual gold figures to be applied to a watch or similar article.

I claim:

The ornamental design for a font of numerals, as shown and described.

FRANCIS E. MEYER.
